(57) **CLAIM**

The ornamental design for a vehicle liftglass assembly, as shown and described.

DESCRIPTION

FIG. 1 is rear-quarter view in perspective of vehicle liftglass assembly in accordance with the invention for closing an opening in the body of a motor vehicle;

FIG. 2 is a top plan view of the vehicle liftglass assembly of FIG. 1;

FIG. 3 is a rear elevational view of the vehicle liftglass assembly of FIG. 1;

FIG. 4 is a side elevational view of the vehicle liftglass assembly of FIG. 1 (the other side elevational view being a mirror image hereof);

FIG. 5 is a bottom view of the vehicle liftglass assembly of FIG. 1; and,

FIG. 6 is an interior elevational view of the vehicle liftglass assembly of FIG. 1.

Broken lines are used in the Drawings to denote certain subject matter, for example, environmental structure or boundaries, that form no part of the design to be patented.
